DOUBLE SASH AND MOISTURE-ABSORBING
RECEPTACLE ASSEMBLY

Oliver M. Edwards, Syracuse, N. Y., assignor to
The O. M. Edwards Company, Inc., Syracuse,
N. Y., a corporation of New York

Original application January 18, 1938, Serial No.
185,565. Divided and this application May 19,
1938, Serial No. 208,856

4 Claims. (Cl. 189—64)

This invention relates to double sash constructions, such as are used in railway cars, buses, and other structures, where it is necessary or desirable to use a moisture-absorbing agent in the space between the glass panes of the double sash, for preventing clouding of the glass, due to differences of temperatures on the inside and outside of the window of the car, bus or other structure; and has for its object a particularly simple construction by which a container for a moisture-absorbing agent is assembled with the sash structure and supported between the glass panes, and further by which it is readily accessible for the purpose of renewing the moisture-absorbing material.

The invention consists in the novel features and in the combinations and constructions hereinafter set forth and claimed.

In describing this invention, reference is had to the accompanying drawing, which is a fragmentary isometric view on an enlarged scale of the double sash window structure embodying this invention.

The window structure is practically the same as that shown in my pending application, Serial Number 185,565, filed January 18, 1938, of which application this is a division.

The invention comprises a receptacle for a moisture-absorbing agent, as activated alumina, extending into the space between the glass panes of the double sash, and being a separate part from the sash structure and readily accessible upon removing of one of the glass panels.

In the illustrated embodiment of the invention, the sash frame is formed in two sections, one section for each glass panel and the receptacle is carried by one of the sections and its companion glass panel and removable therewith and also removable therefrom, so that in removing broken glass pane, the receptacle may be applied to the new glass pane and its sash frame section.

1 designates a window frame formed with a channel 2 for receiving the sash element, the channel having a removable side flange or strip 3, which is clamped against the window frame to clamp the sash in the channel in any suitable manner, as by screws, as shown at 4. The sash frame element here illustrated includes two sections 5, 6, one for each glass panel 7, 8, and the sections here shown are tirelike members of resilient material, as rubber, each formed with a groove 9 for receiving the margin of the glass pane 7 or 8. When the flange or strip 3 is tightened by means of the screws 4, it compresses the resilient section 5 against the other and

tightly seals the sections of the double sash together and in the channel 2, and hence, tightly seals the air space between the glass panes 7, 8. The section 6, which is adjacent the flange or strip 3, is preferably on the inner side of the car, bus or other structure, and is readily demountable, either for the purpose of washing the windows, replacing broken glass, or renewing the moisture-absorbing material. Upon removal of the section 6, the other section 5 and its glass panel is also removable, if desired, but for washing the windows or renewing the activated alumina, it is only necessary to remove the inner section 6 adjacent the flange or strip 3.

10 designates the receptacle for a moisture-absorbing material, as activated alumina, this being carried by the sash section 6 and its glass panel. The receptacle is removable as a unit with the section 6 and its glass 8 and is also separable therefrom. The receptacle includes a 20 lengthwise channel and has a base flange 11 forming an extension of one of the side walls of the channel, and this side wall of the channel and the base flange 11 lies flatwise on the glass pane 8 and extends into the groove 9 of the section 6 and interlocks therein, it being shown as formed with an angular flange 12 hooking around the edge of the glass 8. It is preferably suspended from the upper edge of the glass 8 or from the upper run or top rail of the tirelike 30 member 6 close to the top of the sash, in order to be concealed by the curtain for the window, it being understood that the curtain, when in its completely raised position, laps the sash far enough to cover the receptacle 10. The wall of 35 the channel 10 remote from the other glass 7 is spaced apart therefrom at 13 to form an air circulating space.

In initially assembling the sash with the receptacle 10, the receptacle 10 is placed in juxtaposition to the glass 8 with the flange 12 extending around the edge of the glass, and then the tirelike member 6 placed in position. When it is necessary to renew the moisture-absorbing material or activated alumina in the receptacle 45 10, the flange 3 is demounted, and the section 6 with its glass panel 8 removed, this giving access to the channel 10, so that the moisture-absorbing material may be removed and replaced. In case the glass 8 becomes broken, the flange 3 may 50 be removed and the tirelike member with the splinters or fragments of glass therein removed and the receptacle applied to a new glass, and the new glass mounted in the tirelike member 6 and new 55

5 glass 8 replaced in the window frame. Heretofore, channels for activated alumina have been formed in the sash frame either beyond the edge of the glass pane, between or integral with one
10 of the sash sections on the inner side thereof where it abuts against the other section, so that the sections are not duplicates, or a special cavity has been provided for the activated alumina entirely outside of the sash, or in the corner portions thereof, which recess communicates with the space between the sash through ducts.

15 By the construction here shown, great economy and simplicity result in double sash constructions in which means is provided for receiving a moisture-absorbing material.

15 What I claim is:

1. In a window construction, the combination with a window frame, a double sash mounted in the window frame and including a sash frame element formed with grooves for receiving the margins of spaced apart glass panes; of a receptacle for receiving a moisture-absorbing agent located in the space between the glass panes and having a portion extending into one 25 of the grooves and hooking over the edge of the glass pane in said groove.

2. In a window construction, the combination with a window frame, a double sash mounted in the window frame including a sash frame element formed with grooves for receiving the margins of the spaced apart glass panes; of a receptacle for receiving a moisture-absorbing agent separable from the frame element and extending into the space between the glass panes,

the frame element being so constructed that one of the glass panels is removable independently of the other panel and the receptacle having a base coating with the frame element and said demountable glass panel.

3. In a window construction, the combination with a window frame, a double sash mounted in the window frame including a sash frame element formed with grooves for receiving the margins of the spaced apart glass panes, said element including two separable sections, one around each glass pane, and each section being formed with one of said grooves, and means for clamping the sections against each other; of a receptacle for receiving a moisture-absorbing agent separable from the sections and extending into the space and located entirely between the glass panes and having a base flange coating with and separable from the frame element.

4. In a window construction, the combination with a window frame, a double sash mounted in the window frame including a sash frame element formed with grooves for receiving the margins of the spaced apart glass panes, said element including two separable sections, one 25 around each glass pane, and each section being formed with one of said grooves, and means for clamping the sections against each other; of a receptacle for receiving a moisture-absorbing agent separable from the sections and extending 30 into the space between the glass panes and having a base flange extending into the groove of one of the sections.
